UNITED STATES PATENT OFFICE.

JERRELL BENNETT, OF GRAPEVINE, TEXAS.

PENCIL-LIGHTING ATTACHMENT.

1,280,374.

Specification of Letters Patent. Patented Oct. 1, 1918.

Application filed March 23, 1917, Serial No. 156,911. Renewed February 27, 1918. Serial No. 219,539.

To all whom it may concern:

Be it known that I, JERRELL BENNETT, a citizen of the United States, residing at Grapevine, in the county of Tarrant and State of Texas, have invented new and useful Improvements in Pencil-Lighting Attachments, of which the following is a specification.

This invention relates to illumination, and more especially to portable, self-contained devices for permitting the illumination of a portable article when desired; and the object of the same is broadly to combine an electric lamp with a pencil, pen, or the like mounted within its casing, so that the lamp may be illuminated to light the surface being written on.

The invention is carried out as more fully set forth in the following specification and shown in the drawings wherein:—

Figure 1 is a central longitudinal sectional view of this device complete, showing it adapted for use in connection with a pencil point.

Fig. 2 is a perspective detail showing how the point protrudes through the annular lamp or bulb.

Fig. 3 is an enlarged sectional detail of the annular lamp itself.

Fig. 4 is an enlarged sectional detail showing the circuit closer in a different position from that shown in Fig. 1.

In the drawings the numeral 1 designates the pencil case of tubular formation, and 2 is the removable cap at its front end which when applied covers the tip of the pencil 3. I desire it understood that where I herein speak of a pencil as shown in the drawings, it is quite possible to substitute some other article such as a pen or brush. The rear end of the case in the present instance is open, and temporarily closed by another cap or closure 4. When this is removed access is had to the interior wherein is stored a battery 5 of any appropriate type. Across the case at about its midlength is a partition 6, forward of which the pencil or other instrument 3 is mounted therein in any suitable manner.

In Fig. 3 is best seen the form of lamp or bulb which I preferably employ in this connection. The same has an annular body 10 of glass hermetically sealed as usual, and an annular threaded shank 11 which screwed into an appropriate socket 21 within the casing, and the filament 12 is indicated in

this view as extending completely around the annular body and making convolutions or disposed in other zigzag paths therethrough, the extremities of the filament being connected with the lead wires 22, 23 as shown. The wire 22 is carried down within the case as seen in dotted lines and connected with the lower end of the battery 5 in a manner not necessary to describe in detail.

But an important feature of my invention is the switch or button for throwing the lamp into or out of electrical connection with the battery. This is shown in Fig. 1 as part of the ordinary pocket clip 13 by means of which the case is held to the edge of the vest pocket or the like when it is not in use. This clip is shown as having a knob or ball at its free end, and its other end is rigidly carried by an insulated button 14 slidably mounted in a slot 15 in the side of the casing and in constant contact with the wire 23, the latter being held to but insulated from the casing as at 24 and leading to the bulb as shown. Secured at an appropriate point in the wall of the casing and insulated therefrom is a contact from which a wire 26 leads to the upper end of the battery or batteries 5. The parts are shown in Fig. 1 with the circuit broken, because the ball of the clip does not touch the contact 25. In this condition the operator inserts the device in his pocket and the edge of the latter passes under the ball. In fact,

if he should insert the device in his pocket when the parts stand as seen in Fig. 4, the edge of the pocket would pass between the ball and the contact 25 and the circuit would be broken. However, as soon as he desires to use the device, he removes it from his pocket and slides the clip along in the slot until its tip or ball comes opposite to and falls into touch with the contact 25 so that the current is completed and the light within the bulb is illuminated, and then when he takes off the cap 2 and reverses the device the rays of light from the lamp or bulb are directed along all sides of the pencil point 3 onto the matter being written. The fact that the lamp is annular and the filament extends all around the pencil, prevents the latter from casting a shadow onto that portion of the paper on which the user is about to write, and therefore I consider this is a decided improvement over such an arrangement in which a small lamp or bulb stood alongside the pencil or other instru-

ment. Details other than as herein set forth are unimportant.

What is claimed as new is:—

The herein described illuminated pocket instrument including a casing containing a source of electricity and having a slot in one side, an insulated contact in the same side of the casing connected with one pole of said source, a lamp carried by the casing and connected with the opposite pole of said source, a wire leading from the lamp-socket

within the casing along said slot, a button slidably mounted in said slot in contact with such wire and insulated from the casing, and a spring pocket clip carried by the button and having its free end adapted to touch said contact when the button is at one extremity of the slot, for the purpose set forth.

In testimony whereof I affix my signature. 20

JERRELL BENNETT.
